AUGER-MACHINE FOR BORING BLAST-HOLES.

1,174,163.

Specification of Letters Patent.

Patented Mar. 7, 1916.

Application filed February 6, 1915. Serial No. 6,592.

To all whom it may concern:

Be it known that we, HARRY F. JOHNSTON, GEORGE E. WAGNER, and ROBERT M. DOWNIE, citizens of the United States, residing at Beaver Falls, in the county of Beaver and State of Pennsylvania, have invented a new and useful Auger-Machine for Boring Blast-Holes, of which the following is a specification.

10 This invention has reference to auger machines for boring blast holes, and its object is to bore blast holes of moderate depth in soft rock, coal, soapstone, and hard-pan preparatory to blasting to loosen the over 15 burden in stripping coal measures and ore deposits and in blowing up strata of hard-pan for the purpose of draining old lake beds, etc.

In accordance with the present invention 20 there is provided a vehicle having traction devices and carrying a power unit which may be in the form of a steam engine, an explosion engine, or an electric motor in accordance with the available conditions.

25 The vehicle is provided with a mast or derrick which may be jointed at some convenient point to fold over the vehicle to facilitate transportation. Mounted on the derrick is an auger tube carrying an auger 30 chuck designed to hold a suitable earth auger of sufficient length for the purpose for which the machine is designed, the tube constituting holding and steadyng means for an auger of much greater length than 35 the extent of travel of the tube in feeding the auger, so that the machine will bore a hole of relatively great depth.

The invention contemplates the provision 40 of rotating and feeding means for the auger, which feeding means may supplement the force of gravity in causing the auger to enter the ground and to bore its way through obstructions. Provision is also made for the introduction of the auger into 45 the holding tube and its removal therefrom even though the length of the auger greatly exceed the distance of the chuck from the ground level in the retracted position of the auger tube.

50 The invention will be best understood from a consideration of the following detailed description, taken in connection with the accompanying drawings forming a part of this specification, with the further un-

derstanding that while the drawings show 55 a practical form of the invention, the latter is not confined to any strict conformity with the showing of the drawings, but may be changed and modified so long as such changes and modifications mark no material departure from the salient features of 60 the invention.

In the drawings:—Figure 1 is a side elevation of the auger machine of the present invention with some parts broken away to 65 reveal more distant parts. Fig. 2 is a front elevation of the machine. Fig. 3 is a plan view of the machine. Fig. 4 is a section on the line 4—4 of Fig. 1 but drawn on a larger scale. Fig. 5 is a section on the line 70 5—5 of Fig. 4 with some distant parts omitted. Fig. 6 is an elevation of the carrying plate for the auger tube. Fig. 7 is a longitudinal section through one of the 75 clamps for the auger tube rock-plate, the section also cutting the auger-tube rock and carrying plates.

Referring to the drawings there is shown 80 a body frame comprising sills 1 and connecting cross-pieces 2 wherever needed for imparting rigidity to the frame. The body frame is mounted upon traction wheels 3 and front or steering wheels 4, which latter are controlled by a steering shaft 5 terminating in a steering hand wheel 6 which 85 is carried to a convenient point at the rear of the machine. Mounted on the frame of the vehicle near what may be termed the rear end is a boiler 7 and engine 8 connected by transmission gearing 9 to the traction 90 wheels 3, whereby the machine may be caused to travel from place to place. The boiler and engine may be taken as typical 95 of any motive power for the vehicle, it being sometimes advisable to employ an explosion engine in place of the steam engine shown in the drawings, and under some circumstances an electric motor may be used. The parts so far described, however, may be of any suitable approved construction, and as such construction forms no part of the present invention any specific description of the body structure and motive parts of the machine is deemed to be unnecessary 100 and hence is omitted.

At a convenient point between the ends 105 of the body frame a countershaft 10 is mounted in bearings 11 which in turn are

carried by the sills 1 or upon any suitable supports on the body of the vehicle. This countershaft has fast thereon a sprocket wheel 12 connected by a sprocket chain 13 to another sprocket wheel 14 driven by the engine 8 in any suitable manner. Mounted on the shaft 10 so as to slide therealong and rotate therewith are two spaced friction disks 15, 16, respectively, joined by an elongated hub 17. For convenience of manufacture and operation the disks 15 and 16 and the hub 17 may constitute a single casting, but these parts may be otherwise made so long as they are constrained to rotate with the shaft 10 and may be moved lengthwise thereof, or these parts may be constructed in any other suitable manner, whereby the purpose for which they are provided can be accomplished. Mounted on the hub 17 is a sleeve 18 confined between collars 19 on the hub, and this sleeve is provided with an arm 20 connected by a link 21 to one end of a lever 22 carried by a support 23 which may be in the form of a bracket fast to one of the sills 1. The lever 22 is extended to the front of the machine where it may be formed into or provided with a suitable handle within ready reach of an operator located at the front of the machine, so that the twin disks 15, 16 may be moved along the shaft 10 at the will of an operator for a purpose to be described.

Carried by suitable bearings 24 in turn supported by the main frame is a shaft 25 extending lengthwise of the frame in about its longitudinal mid line. This shaft 25 is provided near the front end with a worm 26 and near the rear end with a friction wheel 27 in position to be engaged by one or the other of the friction disks 15 and 16, but the spacing of these disks is such that but one of them may be brought into engagement with the wheel 27 at a time, and both may be moved so as to be out of engagement with the wheel 27.

Meshing with the worm 26 is a worm wheel 28 carried by a shaft 29 mounted in bearings 30 in turn carried by a frame 31 rising from the sills 1 near the front end of the machine. This frame is connected to and in part supported by upright timbers 32 which in conjunction with corresponding upright timbers 33 constitute the lower or basic part of a mast or derrick erected on the front of the main or body frame of the vehicle for a purpose which will hereinafter appear. The shaft 29 carries drums 34 fast thereto on opposite sides of the worm wheel 28.

Attached to the upper ends of the timbers 32 by hinges 35 are other uprights 36 to which the upper ends of the timbers 33 are secured. Made fast to the upper ends of the timbers 33 are strips 37 in front of the timbers 36 and spaced therefrom a short

distance. Secured to the upper end of what constitutes the upper section of the derrick, which upper section is made up of the timbers 36 and strips 37 with cross pieces 38 and braces 39, are blocks 40 constituting journal bearings for a shaft 41. In order to hold the hinged or upper end of the derrick firmly to the timbers 32 constituting the basic end of the derrick there are provided bolts 42 traversing the timbers 32 and 33 near their lower ends and below the hinge 35. When the bolts 42 are in place the two sections of the derrick are held in an approximately upright position, but when the bolts 42 are removed the upper end of the derrick may be moved in the hinge 35 until this portion of the derrick approaches the horizontal position, thus compacting the structure for transportation. To steady the derrick extended braces 43 are provided, these braces being connected to the timbers 36 near their upper ends and to brackets 44 on the upper ends of uprights 45 erected on the sills 1 near their rear ends, and these uprights 45 are suitably stiffened by brace bars 46 connected to the upper ends of the uprights and extending forwardly to the sills 1. Of course it will be understood that the braces 43 are loosened from the brackets 44 when it is desired to lower the hinged upper end of the derrick. Since the hinging of the derrick and the manner of bracing it is not a part of the present invention and has been heretofore proposed no specific description thereof is deemed to be necessary.

The shaft 41 carries sheaves 47 spaced apart in the direction of the width of the derrick for a distance similar to the spacing of the drums 34. Each drum 34 is encircled by a few turns of a rope or cable 48, there being such a rope or cable for each drum and this rope is preferably, though not necessarily, a wire rope. One end of each rope 48 extends upwardly from the respective drum 34 to the corresponding sheave 47 and over the latter and thence downwardly in front of the derrick to a cross bar 49 to which it is fastened by being formed into a loop 50 with the free end returned upon the rope and there secured by clips 51 in the usual manner. The bar 49 has recesses 52 near the ends each engaged by a hook 53 on one end of a turn buckle 54. The other end of each rope 48 is formed into a loop 55 with the free end of the loop secured to the rope by clips 56. The turn buckles and corresponding ends of the ropes 48 are spread apart farther than the sheaves 47 because of the greater spacing of the portions of the ropes 48 where leaving the drums 34 on being carried to the turn buckles than is the spacing apart of the ropes where leaving the drums 34 and extending to the sheaves 47.

In order to carry the runs of the ropes leading to the turn buckles in front of the derrick, the beams 33 support near their lower ends a rod 57 on which are loosely mounted sheaves 58 about which the corresponding runs of the rope 48 are directed. These sheaves because of their freedom of movement lengthwise of the rod 57 readily accommodate themselves to changing distances apart of the ropes 48.

The bar 49 is formed intermediately of its length into a bearing 59 and is also made fast to a cross head 60 slideable lengthwise of the upper or hinged end of the derrick between the beams 36 and the strips 37 which serve as guides for the cross head. The bearing 59 is traversed by a tube 61 held against lengthwise movement by collars 62 on opposite sides of the bearing. The result of this construction is that the tube may be rotated upon its longitudinal axis in the bearing 59, but cannot move lengthwise thereof. The tube 61 will, however, participate in movements of the cross head up and down the derrick. These movements of the cross head and of the auger tube with it are caused by the ropes 48 which are wound a few turns about the drums 34. Motion is imparted to the drums by the shaft 29 and the worm wheel 28 and worm 26. Motion is imparted to the worm gearing consisting of the worm 26 and worm wheel 28 by engagement of one or the other of the friction disks 15 and 16 with the friction wheel 27, these disks being continuously rotated by connection with the engine or other power unit through the sprocket chain 13, which latter may be taken as typical of any suitable driving connection, whether or not a sprocket chain drive be employed. When one of the disks 15 and 16 is moved into engagement with the friction wheel 27 motion is imparted to the ropes 48 in a direction to lift the cross head 60 and with it the tube 61. When the other friction disk is brought into engagement with the friction wheel the cross head 60 is forced downwardly and the tube 61 participates in such downward movement.

Fast to the beams 33 near their upper ends is a cross plate 63 shown in greater detail in Figs. 4 to 7 than in the other figures. About midway of the length of the plate 63 it is traversed by a stud 64 extending beyond the front of this plate. Mounted on the stud 64 is a rockable plate 65, which plate may for economy of material be made substantially circular. Outstanding from the face of the plate 65 at diametrically opposite points are bearings 66 provided with removable caps 67. These bearings 66 carry a tubular shaft 68 with collars or flanges 68^a in position to engage the bearings 66 to prevent longitudinal movement of the shaft 68 in its bearings without in-

terference with rotation of the shaft. One end of the shaft 68, and this may be the upper end thereof, is formed into or provided with a bevel gear wheel 69 engaged by a bevel pinion 70 on one end of a counter-shaft 71 mounted in journal bearings 72 formed on or carried by the plate 63 near one end thereof. Keyed or otherwise fastened to the shaft 71 at the end thereof remote from the pinion 70 is a sprocket wheel 73 connected by a sprocket chain 74 to a sprocket wheel 75 loosely mounted on a prolongation of the shaft 10 beyond a corresponding one of the sills 1. Mounted on this prolongation of the shaft 10 is a clutch member 76 movable into and out of engagement with another clutch member 77 on the sprocket wheel 75. The clutch member 76 is under the control of an operating lever 78 mounted on a bracket 79 or other support carried by the corresponding sill 1. The lever 78 is prolonged toward the front of the machine into easy reach of an operator.

The gear wheel 69 is formed or provided with a key or spline 80 working in a longitudinal key-way 81 on the tube 61. By this means the tube 61 has rotative movement imparted to it without interference with the movement of the tube 61 longitudinally through the hollow tube driving shaft 68.

The disk 65 is formed on opposite sides with curved slots 82 struck from the center of the disk as an axis. Each slot is traversed by a screw stem 83 threaded into the plate 63 and carrying a screw sleeve provided at the outer end with a manipulating wheel 84. The arrangement is such that the sleeves clamp against the disk 65 to lock it in position, but on turning these sleeves in the appropriate direction the disk 65 is loosened for turning on the stud 64.

The tube 61 at what constitutes its lower end carries a chuck 85 designed to be traversed by an auger 86, which latter may be of a length to extend through the tube 61 and beyond its upper end and also to extend below the chuck toward the ground into close relation thereto when the chuck is at its highest point above the ground. Since the auger is of much greater length than the distance between the highest elevation of the chuck and the ground, and since it is not convenient to insert the auger into the tube 61 through the upper end thereof, the rocker plate or disk 65 is provided. By loosening the clamps on the stems 83 the plate 65 may be rocked upon the stem 64 to bring the auger tube after being released from the bracket 59 at a suitable angle laterally of the front face of the derrick to allow the introduction of the auger into the auger tube through the chuck end thereof. When this is accomplished the parts are returned to and clamped in the upright position with the gear wheel 69 in mesh with the pinion 70

so that the machine is then ready for operation.

When the machine is properly located at the point where the boring is to proceed the 5 auger is so adjusted in the auger tube which is assumed to then be in the highest position with the derrick upright, that the boring end of the auger is in engagement with the ground or about in such engagement. As 10 suming that the engine is in operation the shaft 10 is being continuously rotated but with the disks 15 and 16 out of engagement with the friction wheel 27 and the clutch members 76 and 77 out of engagement the 15 boring tool or auger remains quiescent. To start the auger into rotation the operator moves the lever 78 to engage the clutch members 76 and 77, whereupon the power is transmitted from the sprocket wheel 75 by 20 way of the sprocket chain 74 to the sprocket wheel 73. From the latter through the shaft 71, pinion 70 and gear wheel 69 rotative movement is imparted to the tube 61 and by the latter through the chuck 85 to 25 the auger 86. If the material to be bored is relatively soft the weight of the auger and parts carrying it is sufficient to cause the auger to bore into the relatively soft material and hence it is unnecessary to bring the 30 drums 34 into action except to a degree sufficient to permit the ropes to follow up the lowering movement of the auger and tubular holder therefor, since the worm 26 and worm wheel 28 constitute an effective 35 lock holding the auger and tube carrying it against any lowering movements due to their weight. If the material being bored by the auger offers a resistance superior to the force of gravity acting on the auger, the 40 operator by a manipulation of the lever 22 moves the proper one of the disks 15 and 16 into engagement with the friction wheel 27, whereupon the drums 34 are rotated and the ropes 48 are forcibly propelled in a direction 45 to forcibly lower the cross head 60 and with it the auger tube 61, thus exerting a corresponding force upon the auger, so that it will bore through the resisting material. Ultimately the auger tube is lowered as far 50 as it is intended to travel downwardly, and then the chuck is loosened and by a suitable manipulation of the lever 22 the direction of rotation of the drums 34 is reversed and the auger tube, but not the auger, is lifted 55 to the original high position. When such high position is attained the friction drive is thrown out of action and the chuck is made fast to the auger. During this return movement of the auger tube the clutch members 60 76 and 77 are disengaged, so that the auger tube is not then being rotated. After the parts have been reengaged the clutch members 76 and 77 are again brought into action to cause the rotation of the auger in 65 the manner already described. Further

boring movement of the auger is aided whenever necessary by the feeding force exerted upon the auger by the friction drive acting on the drums 34. When the bore has reached the desired depth, and this may require two or more adjustments of the auger with respect to the auger tube, further rotation of the auger is stopped and the auger is withdrawn by a reversal of the action of the auger tube thereon, the auger being lifted by 75 as many stages as were necessary to drive it into the ground.

Whenever it is necessary or desirable to remove the auger from the auger tube or insert it therein the auger tube is rocked 80 upon the stud 64 as an axis until the angular relation of the tube to the derrick is such as to permit the desired manipulation of the auger.

The tubular auger holder may, of course, 85 be of skeleton form instead of a continuous-wall tube or of any other suitable construction so long as it serves as a holder and guide for the auger, and the word tubular is to be so understood.

What is claimed is:—

1. A machine for the purpose described, provided with an elongated tubular auger holder having a chuck at one end for securing an elongated auger of greater length 95 than the holder at any point along the length of the auger, said holder being freely open throughout its bore of a size to be traversed by the auger, means for rotating the holder, and means independent of the 100 means for rotating the holder for positively moving said holder lengthwise in either direction.

2. In a machine for the purpose described, a derrick, a normally upright elongated tubular holder thereon provided at the lower end with means for securing an elongated auger thereto at any point along the length of said auger and the tubular holder also having a free bore throughout open at both 110 ends and of a diameter to be wholly traversed by the auger, means for positively moving the holder lengthwise in either direction, and means for rotating the holder, said last-named means being independent of the 115 means for moving the holder lengthwise.

3. A machine for the purpose described, comprising a derrick, an open ended sleeve mounted on the derrick for rocking movements about an axis perpendicular to the 120 length of the sleeve, an open ended tube traversing the sleeve and participating in the rocking movements thereof, the bore of the tube being of a size to be traversed by an elongated earth-entering auger and the 125 tube having a chuck at one end for securing the auger thereto at any point along the length of said auger, means for positively moving the tube longitudinally in either direction, and means for rotating the sleeve, 130

- said tube being connected to the sleeve for participating in the rotary movements of the latter and the means for rotating the sleeve being independent of the means for moving 5 the tube lengthwise.
4. A machine for the purpose described provided with a tubular auger holder having a chuck at one end for securing an elongated earth entering auger thereto, said holder 10 being freely open throughout and having its bore of a size to be traversed by the auger, means for rotating the tubular holder, and a single means independent of the means for rotating the holder for positively advancing 15 said holder lengthwise to feed the auger and for retracting the holder independently of the auger.
5. In a machine for the purpose described, a derrick, an elongated tubular auger re- 20 ceptacle and holder, a mounting for the holder on the derrick movable with the holder about an axis perpendicular to the length of the holder and derrick, whereby the holder may be moved from a substan- 25 tially upright working position into angular relation to said working position for the introduction and removal of an elongated auger a plurality of times the length of said holder, separable means for rotating the 30 holder about its longitudinal axis in position on the derrick to rotate the holder when in the upright working position only, and means independent of the means for rotating the holder positively imparting lengthwise 35 movement to the holder and having means for driving it in either direction at the will of an operator.
6. In a machine for the purpose described, a derrick, an elongated tubular auger holder, 40 a mounting for the auger on the derrick movable about an axis perpendicular to the length of the holder and derrick to carry said holder from a substantially upright working position into angular relation there- 45 to for the introduction and removal of an elongated auger a plurality of times the length of said holder, separable means for rotating the holder about its longitudinal axis with the part of the holder-rotating 50 means on the holder movable therewith out of engagement with the remainder of said holder-rotating means, whereby the holder is rotated when in the upright position only, and means independent of the holder-rotat- 55 ing means for positively imparting length- wise movement to the holder in both direc- tions and having means for driving said last-named means in either direction at the will of an operator.
7. In a machine for the purpose described, a derrick, a rockable mounting thereon, a 60 rotatable hollow shaft on the rockable mounting, driving means for the shaft, an elongated hollow tubular member movable lengthwise through the hollow shaft and 65 connected thereto for rotative movements by said hollow shaft and also provided with means for securing an elongated earth-entering auger thereto, a cross head carried by the derrick and movable lengthwise thereof and 70 connected to the tubular member for causing lengthwise movements thereof, and interior means for positively moving the cross head in either direction to impart corresponding movements to the tubular member. 75
8. In a machine for the purpose described, a derrick, a rockable mounting thereon, a rotatable hollow shaft on the rockable mounting, driving means for the shaft, an elongated hollow tubular member movable 80 lengthwise through the hollow shaft and connected thereto for rotative movements by said hollow shaft, and also provided with means for securing an elongated earth-entering auger thereto, a cross head carried by 85 the derrick and movable lengthwise thereof and connected to the tubular member for causing lengthwise movements thereof, and means for moving the cross head in either direction to impart corresponding move- 90 ments to the tubular member, said last-named means comprising unitary rope ac- tuating-means for the cross head connected to opposite sides thereof, a unitary drum drive for said rope means to move it posi- 95 tively in opposite directions, and driving means for the drum drive including direc- tion reversing means.
9. In a machine for the purpose described, a derrick, a rockable mounting thereon, a 100 rotatable hollow shaft on the rockable mounting, driving means for the shaft, an elongated hollow tubular member movable lengthwise through the hollow shaft and connected thereto for rotative movements by 105 said hollow shaft and also provided with means for securing an elongated earth-entering auger thereto, a cross head carried by the derrick and movable lengthwise thereof and connected to the tubular member for 110 causing lengthwise movements thereof, and means for moving the cross head in either direction to impart corresponding move- ments to the tubular member, said last-named means comprising a unitary rope ac- 115 tuating-means for the cross head connected to opposite sides thereof, a unitary drum drive for said rope means to move it posi- tively in opposite directions, and driving means for the drum drive comprising direc- 120 tion reversing means consisting of a friction wheel, worm gear connections therefrom to the drum drive, and oppositely acting friction disks movable together into individual engagement with the friction wheel. 125
10. In a machine for the purpose de- 130 scribed, a derrick, an auger holder mounted on and movable longitudinally of the derrick, and means for moving the auger holder positively in both directions, comprising

6

ropes each connected at both ends to the holder with direction-changing sheaves around which the ropes pass to reverse the direction of their runs, drums having friction turns of the ropes about them, a worm gear connected to the drums for driving them, and a friction gear for driving the worm gear comprising a friction wheel and connected disks spaced apart by a greater distance than the diameter of the friction wheel and movable individually into engagement with the friction wheel at respectively opposite sides thereof to change the direction of movement of the friction wheel or to remain in idle relation thereto, at will.

11. In a machine for the purpose described, a derrick, an elongated tubular holder mounted thereon for movement lengthwise thereof, means for rotating the holder, a cross head guided on the derrick and connected to the tubular member for moving it positively in opposite directions, and means for imparting positive movements to the cross head comprising ropes each connected at opposite ends to the cross head, sheaves at the top and bottom portions of the derrick and around which the ropes pass for changing the direction of their runs, drums with friction turns of intermediate portions of the ropes about them, a worm gear for driving the drums, and locking the drums in the inactive position, and a friction gear for driving the worm gear having means for reversing the direction of movement of the worm gear and constructed to allow the worm gear to remain in the inactive position.

12. In a machine for the purpose described, a derrick, an elongated tubular holder mounted thereon for movement lengthwise thereof, means for rotating the holder, a cross head guided in the derrick and connected to the tubular member for moving it positively in opposite directions, and means for imparting positive movements to the cross head comprising ropes each connected at opposite ends to the cross head, sheaves at the top and bottom portions of the derrick around which the ropes pass for changing the direction of their runs, drums with friction turns of intermediate portions of the ropes about them, a worm gear for driving the drums and locking the drums in the inactive position, and a friction gear for driving the worm gear having means for reversing the direction of movement of the worm gear and constructed to allow the worm gear to remain in the inactive position, said derrick being also provided with mechanism for imparting rotative movements to the tubular holder.

13. In a machine for the purpose described, a derrick, an elongated tubular auger holder thereon having a normal upright position on the derrick and provided

with a chuck at the lower end for securing an elongated earth-entering auger thereto, said auger being a plurality of times the length of the holder and the latter being of an inner diameter throughout to be traversed by the auger, and a mounting for the tubular holder rockable on the derrick about an axis perpendicular to the length of the derrick, said mounting and tubular holder having a range of movement from a normal upright position to an inclined position permitting the reception in and removal from the holder of the elongated auger.

14. In a machine for the purpose described, a derrick, a rockable plate thereon having curved slots therein, clamp screws extending through the slots for securing the plate in different positions of rotation about an axis perpendicular to the length of the derrick, a hollow drive shaft mounted on the plate and including a gear wheel in eccentric relation to the axis of rocking of the plate, means on the derrick for rotating the shaft through the gear wheel, and an elongated tube mounted in the hollow shaft and movable lengthwise thereof and coupled thereto for rotation therewith, said tube having a bore for the reception of an elongated earth-entering auger, and a chuck at one end for securing the auger to the tube at any point along the length of said auger.

15. In a machine for the purpose described, a derrick, a plate mounted thereon for rocking movements on an axis perpendicular to the length of the derrick and provided with slots concentric with the axis of rotation, clamp screws extending through the slots for holding the plate in adjusted positions of rotation about its axis, bearings on the plate, a hollow shaft mounted in the bearings and carrying a gear wheel in eccentric relation to the axis of rocking of the plate, a shaft mounted on the derrick and provided with another gear wheel normally meshing with and toward and from which the first named gear wheel is movable with said plate, driving connections for the shaft including a throw out clutch, and an elongated tube mounted in the hollow shaft and movable lengthwise thereof, said tube being connected to the hollow shaft for rotation therewith and provided with a chuck at one end for the reception of an elongated earth-entering auger, said chuck and tube being of an internal size to permit the tube to be traversed by the auger and to engage and hold the auger at any point along the length thereof.

16. In a machine for the purpose described, a derrick, a plate mounted thereon for rocking movements on an axis perpendicular to the length of the derrick and provided with slots concentric with the axis of rotation, clamp screws extending through the slots for holding the plate in adjusted

- positions of rotation about its axis, bearings on the plate, a hollow shaft mounted in the bearings and carrying a gear wheel in eccentric relation to the axis of rocking of the 5 plate, a shaft mounted on the derrick and provided with another gear wheel normally meshing with and toward and from which the first named gear wheel is movable with said plate, driving connections for the shaft 10 including a throw out clutch, and an elongated tube mounted in the hollow shaft and movable lengthwise thereof, said tube being connected to the hollow shaft for rotation therewith and provided with a chuck at one 15 end for the reception of an elongated earth-entering auger, said chuck and tube being of an internal size to permit the tube to be traversed by the auger and to engage and hold the auger at any point along the length 20 thereof, said tube having means attached thereto for positively moving it lengthwise in either direction.
17. In a machine for the purpose described, a derrick, an auger holder mounted 25 on and movable longitudinally of the derrick, and means for moving the auger holder positively in both directions comprising
- ropes each connected at both ends to the holder and including take-up means for regulating the tension of said ropes, drums 30 having friction turns of the ropes about them, and means for driving the drums.
18. In a machine for the purpose described, a derrick, an auger holder mounted on and movable longitudinally of the derrick, and means for moving the auger holder positively in both directions comprising 35 ropes each connected at both ends to the holder and including turn-buckles for regulating the tension of said ropes, drums having 40 friction turns of the ropes about them, and means for driving the drums.

In testimony, that we claim the foregoing as our own, we have hereto affixed our signatures in the presence of two witnesses.
